UNITED STATES PATENT OFFICE

156,046

DESIGN FOR A BOTTLE

Victor Silson, New York, N. Y., assignor to Helena Rubinstein, Inc., New York, N. Y., a corporation of New York

Application August 7, 1948, Serial No. 147,989

Term of patent 7 years

(Cl. D58—8)

To all whom it may concern:

Be it known that I, Victor Silson, a citizen of the United States of America, residing at 24 West 55th Street, New York city, in the county of New York and State of New York, have invented a new, original, and ornamental Design for a Bottle, of which the following is a specification, reference being had to the accompanying drawing, forming part thereof.

In the drawing:

Fig. 1 is a top plan view of a bottle showing my new design;

Fig. 2 is a side elevational view; and

Fig. 3 is a bottom view of the same.

I claim:

The ornamental design for a bottle, as shown.
VICTOR SILSON.
